DESIGN FOR A COMBINED SHAFTLESS PROPELLER AND SUPPORT THEREFOR

William Waterval, Brooklyn, N. Y.

Application June 6, 1941, Serial No. 101,327

Term of patent 3½ years

(Cl. D71—1)

To all whom it may concern:

Be it known that I, William Waterval, a citizen of the United States, residing at 4614 6th Avenue, Brooklyn, in the county of Kings and State of New York, have invented a new, original, and ornamental Design for a Combined Shaftless Propeller and Support Therefor, of which the following is a specification, reference being had to the accompanying drawing, forming part thereof, and in which:

Figure 1 is a top plan view of a combined shaftless propeller and support therefor, showing my design.

Figure 2 is a side elevational view of the same.

Figure 3 is a rear elevational view thereof; while

Figure 4 is a bottom plan view of my device; and

Figure 5 is a vertical sectional view taken on the line 5—5 of Figure 3.

I claim:

The ornamental design for a combined shaftless propeller and support therefor, as shown.

WILLIAM WATERVAL.
